UNITED STATES PATENT OFFICE.

PARKER F. MOREY, OF CHICAGO, ILLINOIS, ASSIGNOR OF ONE-HALF HIS
RIGHT TO AURELIUS V. PITTS, OF SAME PLACE.

IMPROVEMENT IN JOURNAL-BEARINGS.

Specification forming part of Letters Patent No. 154,764, dated September 8, 1874; application filed
April 7, 1874.

To all whom it may concern:

Be it known that I, PARKER F. MOREY, of Chicago, in the county of Cook and State of Illinois, have invented a new and useful Improvement in Journal-Boxes; and I do hereby declare the following to be a full, clear, and exact description thereof, which will enable others skilled in the art to which my invention appertains to make and use the same, reference being had to the accompanying drawing, forming part of this specification, in which—

Figure 1 is a vertical longitudinal central section through the lower portion of a car-box embodying my said invention. Fig. 2 is a top view of the same, and Fig. 3 is a transverse section taken on the line x x drawn across Figs. 1 and 2.

Similar letters of reference indicate like parts in the several figures of the drawing.

The object of my invention is to so construct the box as to allow the filling to come in contact with the shoulders of the axle, and at the same time allow the filling to be removed when worn without injury to the shell of the box; and to that end it consists in providing the shell, near the ends, with transverse grooves, within which are fitted adjustable shoulders having a series of channels, through which the filling passes, forming the shoulder bearing against the shoulders of the axle, as will be more fully understood by the following description.

In the drawing, A represents the shell or body of the box, which is made in the usual manner. B B are shoulders, which are loosely fitted into circular dovetail grooves formed across and within the walls of the box, as shown in Figs. 1 and 2. These shoulders are

arranged at a slight distance from the ends of the box, and are so shaped on their inner face as to fit the circumference of the axle, and are provided with a series of transverse channels, a a, as shown in Fig. 3. C is the filling, which is made of the usual metals.

The shoulders B B are so fitted within the grooves as to admit of being adjusted or removed when necessary. The object of the shoulders is to prevent the filling from moving in the direction of its length; and, by arranging them at a slight distance from the ends of the body of the box and providing them with the channels a a, the filling is allowed to pass through the channels and fill the space between the outer surface of the shoulders and end of the box, thus bringing the filling in contact with the shoulders of the axle.

In constructing the box I usually make the body portion of ordinary cast-iron; consequently the same is much cheaper than when made from the material commonly used, and, as the filling can be removed when worn and the body refilled, the box is more durable and convenient than those now in use.

Having thus described my invention, I claim—

The adjustable shoulders B B, provided with the channels a a, and combined with the block A and filling C, as and for the purpose specified.

The above specification of my invention signed by me this 17th day of January, 1874.

PARKER F. MOREY.
